CENTRIFUGAL TUYÈRE

Bruce R. Wright, Cleveland, and Foster F. Hillix,
Lakewood, Ohio, assignors to Centrifix Corporation,
Cleveland, Ohio, a corporation of Ohio

Application May 19, 1949, Serial No. 94,124

7 Claims. (Cl. 183—80)

1

This invention is an improvement in the art of separating various substances from flowing fluids and relates more particularly to an improved centrifugal separating device and tuyère of the fixed type for separating entrained substances from a carrier fluid.

One of the difficulties heretofore encountered in the separation of entrained substances from a carrier fluid has been the inability to prevent re-entrainment of wild drops of liquid or particles after the same have once been separated or disentrained from the carrier fluid.

It is one of the principal objects of the present invention to eliminate this disadvantage and to provide means which will efficiently separate an entrained substance from a carrier medium without permitting re-entrainment of any part of the separated substance with the carrier medium.

Another object of our invention is the provision of a separator of the type described which is extremely simple in construction and which lends itself to economical manufacture and which is highly efficient in use.

A further object of our invention consists in a separator employing a tuyère of the fixed type which is so designed that it substantially eliminates all vortex action.

Another object of the invention is a separator employing a tuyère which is substantially conical in shape and which is provided with a multiplicity of blades arranged in a pattern around the tuyère, there being provided means by which substances separated from the carrier medium passing through the tuyère may be guided and directed along the blades in a direction from the apex of the tuyère toward its base and thence between the adjacent blades to the internal wall of the casing, where the separated substances are then caused to travel toward and through a drain or outlet.

Another object of the invention consists in a separator of the above mentioned type which is characterized by a higher degree of efficiency over the conventional centrifugal separators of the prior art, and which further possesses the ability to separate entrained substances from a carrier medium over a much wider range of gas and vapor flow than is possible with the conventional type of centrifugal separators. Furthermore, the invention will function efficiently at very low flows as distinguished from less efficient operation of the conventional type of separator.

Other objects and advantages of our invention will become more apparent as the following description of an embodiment thereof progresses.

reference being made to the accompanying drawings in which like reference characters are employed to designate like parts throughout the same.

5 In the drawings:

Figure 1 is a perspective view of a tuyère embodying our invention,

Figure 2 is a view similar to that shown in Figure 1 showing the tuyère from below and 10 within,

Figure 3 is a development view illustrating the manner in which the tuyère may be punched out prior to its being rolled or formed into substantially conical shape as shown in Figures 1 and 2,

15 Figure 4 is a section taken on line 4—4 of Figure 3,

Figure 5 is a top plan view of the tuyère shown in Figures 1 and 2,

Figure 6 is a vertical section through the tuyère 20 taken on line 6—6 of Figure 5,

Figure 7 is a sectional view of a separator embodying our invention showing the inlet fitting and our improved tuyère, and,

25 Figure 8 is a vertical section through a separator embodying our invention illustrating in addition to the tuyère the drain and outlet ports together with means for preventing wild drops or particles below the tuyère from being re-entrained in the outlet passage.

In carrying out our invention we have shown 30 the same applied to a separator unit in Figures 7 and 8 of the drawings in which the separator shell or casing 1 is provided with an inlet or fitting 2 at its upper end in axial alignment with the casing, the upper portion of the walls forming the inlet chamber 3 being domed at 4 from the sides of the casing upwardly and inwardly toward the fitting 2. The fitting 2 may be threaded internally to receive a threaded conduit through which the carrier medium and the entrained sub-

35 stances are caused to enter the receiving chamber 3. A tuyère 5 having a base band 6 and a plurality of blades 7 integral therewith is disposed within the casing 1 and permanently secured thereto by welding or the like, the vertical axis of the tuyère being in alignment with the axis of the casing 1. Vertically disposed within the casing 1 is an outlet passage 8. This passage opens below the bottom of the tuyère 5 and is adapted to transmit the unladen carrier medium therethrough to a suitable point of disposal while the substances disentrained from the carrier medium are caused to travel downwardly from the base of the tuyère and the blades there- 40 of along and in contact with the inner wall of

the casing where they may be drained through the drain fitting 9. If desired a vent 10 may be provided for the casing 1.

Referring now more particularly to Figures 1 to 6 inclusive in which we have illustrated in detail the construction of a form of tuyère embodying our invention, it will be seen that we have provided a tuyère which may be constructed at low cost and by simple mechanical methods such as by stamping or punching the same from a sheet of material. Referring more particularly to Figure 3 in which the tuyère is shown in a developed view, the tuyère unit 5 comprises a base band 6 and a plurality of blades 7 formed integral therewith and projecting upwardly from the base. Each of the blades is identical and converges upwardly from its base terminating in a free end 11. As shown in Figure 4 a portion along one longitudinal edge of each of the respective blades is provided to form a ledge for purposes which will be described more fully hereinafter.

In forming the tuyère to conical form as illustrated in Figures 1, 2, 5 and 6, the blank is rolled to circular form the free ends of the blades converging to form an apex 5a, while the longitudinal portions along one edge of each of the blades 7, as at 12, are formed or disposed outwardly of the axis of the tuyère. The base of each blade is formed along the broken lines 13, 14 and 15 to provide a guide surface 16 which projects downwardly toward the base ring 6 thus disposing the blade in a plane intersecting the base band 6. The leading edge 17 of each blade will thus extend from the upper portion of the band directly to the top of the blade at the apex of the tuyère while the trailing edge 18 carrying the outwardly formed guiding ledge 12 will be disposed in a direction from within the confines of the band to the top of the tuyère, the trailing edge 18 and ledge 12 of each blade being thereby spaced from the next adjacent blade looking in a counter-clockwise direction in Figure 1 so that they will underlie in spaced relation the leading edge of the said next adjacent blade. The space 19 between each of the adjacent blades is provided for the passage of the carrier fluid from a point outside the tuyère to within the tuyère. It is to be noted that the leading portion of each of the blades at and adjacent the leading edge 17 lies in the periphery of the base band 6, while the trailing portion is disposed inwardly of the band periphery and in a plane intersecting the periphery of the band 6. The relation of the blades with respect to the base band 6 is such that the carrier fluid and the entrainment passing between the blades will be caused to whirl in a counter-clockwise direction in Figure 5, at a velocity sufficient to liberate the entrained matter in the carrier fluid.

Referring again to Figure 3 that portion of the tuyère indicated in the substantially triangular area at 20 is removed from the respective blades. This is for purposes of clearance and further to provide an unobstructed path for the disentrained matter collecting on and passing along the blades and their respective ledges 12 to the inner wall of the band 6 as at 21.

It will be noted that the passages 19 between adjacent blades are narrow and extend from a point adjacent to and behind the base ring 6 to a point very closely adjacent the apex 5a of the tuyère.

The operation of our invention may be described as follows:

A laden carrier fluid is directed axially into the casing 1 through the inlet 2 and, entering the chamber 3, will strike the tuyère 5 first at the apex thereof and thence downwardly, the major portion of the entrainment or mist impinging upon blades 7 to be guided downwardly along the blades and the ledges 12 and away from the center or axis of the tuyère to the outer edge of the tuyère at the base of the blades 7 where the entrainment will then pass over the surfaces 16 and through the openings between the blades and continue on downwardly along the inside wall of the casing 1. Because of the substantially tangential pattern of the blades, the carrier medium passing therebetween will form a whirling mass. During this action, any entrainment impinging on the blades 7 and tending to travel transversely of the blades toward the ledges 12 will be caught thereby and thence led downwardly of the blades 20 to a point where it will join with other entrainment, such as that which passes through the openings in the cone section which is thrown to the outside edge of the whirling mass where it joins other entrainment that does not get through the openings between the respective blades.

It will be noted that by virtue of our invention there is no tendency for any of the entrainment to flow toward the center or axis of the tuyère, or its apex. This is due primarily to the fact that the openings between the blades extend up close to the apex of the conical tuyère and thereby allow fluid to pass into the vortex of the whirling mass within the tuyère, thus breaking what would otherwise be a low-pressure area in this location. Under such circumstances the tendency to draw disentrained substances back into entrainment is avoided.

It should be understood that with our invention all of the entrainment is led or guided to the inside wall of the casing by means of the blades 7, the ledges 12 and the surfaces 16 in a continuous guided path without the necessity of causing the entrainment to jump across gaps as is the case in the conventional type of centrifugal separators with which we are familiar. It will be seen, therefore, that by virtue of the present invention re-entrainment of the separated substances is eliminated.

Referring again to Figure 8, we have illustrated means whereby to prevent the re-entrainment in the outlet passage 8 of stray or wild drops or particles which occasionally break loose from the whirling mass and approach the open end of the outlet tube 8.

Such means may comprise a circular member 38 mounted on the upper end of the outlet tube 8, said member being formed with a series of spaced blades 39 arranged in a helical pattern around the member 38. Thus wild drops or particles landing near the open end of the outlet 8 are guided away and eventually pass to the bottom of the casing and out through the drain 9.

Various changes may be made in the details of construction and arrangement of parts of our invention without departing from the purposes of the invention or the scope of the appended claims.

We claim:

1. In a centrifugal separator, a casing having a fluid inlet passage and an outlet passage, and means between said passages for imparting a whirl to a fluid stream passing through said casing, said means comprising a tuyère of conical form secured at its base to the inner wall of said casing, said tuyère comprising a plurality of blades supported at their bases on said tuyère

base and converging at their upper ends to form an apex adjacent one of said passages, said blades each having one edge formed out of the plane of blade to provide a ledge for capturing entrainment impinging on said blades and guiding the same toward said base and to said casing inner wall.

2. A whirl imparting tuyère for centrifugal separators comprising as a unitary structure a body of general hollow conical form including a base portion and a plurality of blades converging from said base portion, each of said blades having an edge formed out of the plane of the blade and within the confines of the base portion to provide a guide for entrainment impinging on said blades, whereby said entrainment is guided along said blades and along the inner surface of said base to the inner wall of said casing.

3. A whirl imparting tuyère for centrifugal separators comprising as a unitary structure a body of general hollow conical form including a base portion and a plurality of blades spaced in overlapping relation and converging from said base portion, each of said blades having an edge formed out of the plane of the blade to provide a guide for entrainment impinging on said blades, whereby said entrainment is caused to move along said blades and over the inner surface of said base, said entrainment guiding edge of the respective blades being spaced from and underlying the adjacent edge of an adjacent blade.

4. A whirl imparting tuyère for centrifugal separators comprising as a unitary structure a body of general hollow conical form including a base portion and a plurality of overlapping blades converging from said base portion, each of said blades having an edge formed out of the plane of the blade to provide a guide for entrainment impinging on said blades, whereby said entrainment is caused to move along said blades and over the inner surface of said base, said entrainment guiding edge of the respective blades being spaced from and underlying the adjacent edge of an adjacent blade, each of said blades having a surface connecting the blade with said base and lying out of the planes of the blade and said guide portion.

5. A whirl imparting tuyère for centrifugal separators comprising as a unitary structure a body of general hollow conical form including a base portion and a plurality of overlapping blades converging from said base portion, each of said blades having an edge formed out of the plane of the blade to provide a guide for entrain-

ment impinging on said blades, whereby said entrainment is caused to move along said blades and over the inner surface of said base, said entrainment guiding edge of the respective blades being spaced from and underlying the adjacent edge of an adjacent blade substantially throughout the length of said blades.

6. In a centrifugal separating device, a casing having an inlet for an entraining fluid, an outlet, a conical tuyère device fixed in said casing between the inlet and outlet and providing the only means of fluid passage between the same, said tuyère comprising a base secured to the inner wall of said casing, a plurality of blades converging from said base to form an apex portion near said inlet, said blades each having an edge portion formed outwardly of said blade to capture entrainment impinging upon said blade and to guide the same toward said base inner surface and thence directly to said casing inner wall, and means in said casing and associated with said outlet for preventing re-entrainment of wild drops or particles with the unladen fluid passing into said outlet.

7. In a centrifugal separator, a combination with a casing having an inlet passage and an outlet passage of a tuyère in said casing and between said passages, said tuyère having a base secured directly to the inner wall of the casing and a plurality of tuyère blades converging from said base and out of contact with said casing inner wall to form an apex projecting axially toward one of said passages, the leading portions of said respective blades at the base thereof lying substantially in the periphery of said base, the trailing portions of said blades being disposed inwardly of said base periphery and lying in planes intersecting said base periphery.
